BACK HOE

Clarence G. Grube, 12510 W. Lisbon Ave.,
Brookfield, Wis.

Filed Jan. 31, 1964, Ser. No. 78,452

Term of patent 14 years

(Cl. D40—1)

FIG. 1 is a perspective view of a back hoe embodying the new design.

FIG. 2 is a perspective view of the same taken from the rear.

The dominant features of my design reside in the full line portion as shown.

I claim:

The ornamental design for a back hoe, as shown and described.
